CENTERING DEVICE FOR CAR COUPLERS

William J. Metzger, Euclid, Ohio, assignor to National Malleable and Steel Castings Company, Cleveland, Ohio, a corporation of Ohio

Application October 17, 1941, Serial No. 415,395

11 Claims. (Cl. 213—21)

This invention relates to centering devices for railway car couplers and more particularly to a centering device of the releasable type.

In the past couplers provided with centering devices have been subject to damage during attempted coupling of cars on curves. Since a centering device maintains a free coupler in central position, if the curve on which two cars to be coupled are located is of sufficiently small radius, the mating couplers may not be within their gathering range and may be damaged by jack-knifing or otherwise, as the cars come together. Accordingly, it is an object of my invention to provide a centering device which is quickly releasable from its functioning relationship with respect to the coupler to permit angling thereof to any desired position and thereby enable proper coupling on curved tracks. Another object is to provide a novel releasable centering device for car couplers which is simple in construction and which is automatically locked into normal operative position upon return of the coupler to centered position from a released angled position.

Other objects and advantages of my invention will be apparent from the following description taken in conjunction with the drawings, in which:

Figure 1 is a front view partly in section of a centering device embodying my invention.

Figure 2 is a plan view partly in section, taken along line 2—2 of Fig. 3.

Figure 3 is an end view of the construction shown in Fig. 1, the carrier iron being shown in section.

Figure 4 is a bottom plan view of the device.

Figure 5 is a view similar to Fig. 3, with the lock member removed.

Figure 6 is a plan view of the centering spring yoke member.

Figure 7 is a fragmentary plan view of the lock member; and

Figure 8 is an end view of the lock member.

Referring to the drawings, there is shown the carrier iron 10 upon which the resilient supporting mechanism 11 is slidably mounted. The coupler 12 is carried by this mechanism the various features of which are described and claimed in my copending application Serial No. 347,342, filed July 24, 1940. The carrier iron 10 is provided with support flanges 13 which are received in recesses 14 in the vertical support columns 15. Bolts 16 secure the carrier iron to the columns and are relieved of vertical load by flanges 13. Although the carrier iron is shown as a sepa-

rate member it is to be understood that it may be formed integral with columns 15 without departing from the spirit of the invention. The carrier iron is formed with horizontal top and bottom walls 17 and 18 respectively and a vertical connecting side wall 19. Within the recess formed by these walls is positioned the centering spring 20, each end thereof engaging the space abutments or stop flanges 21 and 22. Embracing spring 20 is the yoke member 23, the end portions 24 thereof fitting between the ends of flanges 21 and 22 and thus permitting longitudinal sliding of the yoke relative to the carrier iron against the compression of the spring. The yoke is formed with side straps 25 and 26, strap 25 being received within a recess 27 in side wall 19. The top and bottom walls of the carrier iron are recessed as at 28 and 29 to receive side strap 26 of the yoke. It will be observed that strap 26 serves to complete the enclosure of spring 20, precluding entry of any foreign matter into the spring chamber as would interfere with the operation of the device.

The saddle member 35 which is adapted to slide along top wall 17 of the carrier iron has depending flanges 36 and 37 embracing the latter and serving to maintain the saddle in position thereon as the coupler angles in service. Flange 37 being adjacent strap 26 of the yoke serves to hold the latter in place within the carrier iron. At each end of flange 37 there is provided an integral bracket 38 for pivotal mounting of the lock member 39. Lugs 40 which project from the horizontally extending body portion 41 of the lock member are adapted to be received by brackets 38, the pivotal connection being made by means of bolts 42 carried in the brackets and extending through apertures in the lugs. Each of lugs 40 is formed with a stop 44 adapted to engage bracket 38 as at 45 to limit upward movement of the lock member when the latter is operated to release the saddle from the influence of spring 20. At each end of the lock member is an operating handle 43 for manipulation of the device from either side of the coupler.

In order to lock the yoke and saddle from relative movement therebetween so that centering spring 20 will be in operative relation therewith, stop lugs 46 on the yoke and projections 47 on the lock member are provided. In locked position of member 39 projections 47 are positioned adjacent the ends of lugs 46, and as the saddle member slides along the carrier iron in response to horizontal angling of the coupler the

yoke moves therewith, causing spring 29 to be compressed. This compression acts to return the coupler to central position, and when the coupler is free, it will always be maintained in a central position.

To release the connection between the yoke and saddle member and thus render the centering device inoperative the lock member is pivoted by raising either of handles 43 until projections 47 are out of engageable relationship with stop lugs 46 on the yoke, as shown in dot-dash lines in Fig. 3. The saddle member may then be freely moved along the carrier iron to any angled position of the coupler desired within the range of movement of the saddle member. In this released position of the device the yoke remains stationary as the saddle member is moved along the carrier iron. Handles 43 may be used to move the saddle member in addition to being used to operate the lock member during releasing of the centering device. Furthermore, once the saddle member has been disengaged from the yoke and displaced from central position, handles 43 which previously had been raised may be dropped to reposed position, after which no further attention need be given to the lock member, and the parts will become locked automatically when the coupler reaches its central position. This action is made possible by sloping the sides of lugs 46 on the yoke from near the outer ends thereof to the side of strap 26, as at 48. Thus with the device disengaged and the saddle moved along the carrier iron so that one of projections 47 is located intermediate lugs 46 and in engagement with the side of strap 26, upon movement of the saddle toward central position, portion 49 of handle 43 or projection 47 will slide along surface 48, causing the lock member to pivot upwards. This raising of the lock member continues until the saddle reaches central position at which point the lock member will drop into normal locked position with projections 47 in engageable relation with lugs 46, as shown particularly in Fig. 4. It will be observed that in all operative positions of the lock member the preponderance of the weight thereof is located outwardly of pivots 42 and therefore acts to return the member to locked position and to maintain it therein.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A centering device comprising a carrier iron having a recess therein, a saddle slidably mounted on said carrier iron and adapted to support a coupler, spring means positioned between stops within said recess, a yoke mounted within said recess embracing said spring and adapted to slide relative to said carrier iron in a direction longitudinally thereof against the compression of said spring, and means on said saddle adapted to be moved into and out of engageable relation to said yoke for releasably connecting said saddle to said yoke.

2. A centering device comprising a carrier iron having a recess therein, a saddle slidably mounted on said carrier iron and adapted to support a coupler, a spring positioned between stops in said recess and adapted to be placed under compression therein, a member mounted in said recess

embracing said spring and adapted to compress the latter upon moving relative to said carrier iron in a direction away from its central position, and means on said saddle adapted to be moved into and out of engageable relation to said member for releasably connecting said saddle to said member.

3. In a centering device a carrier iron, a saddle slidably mounted on said carrier and adapted to support a coupler, a spring carried by said carrier iron and positioned between stops therein, a yoke carried by said carrier iron embracing said spring and adapted to slide relative to said carrier iron against the compression of said spring, and releasable means on said saddle and yoke in one position connecting said saddle and yoke and in another position allowing movement of said saddle on said carrier iron without compressing said springs.

4. In a centering device a carrier iron having a recess therein, a saddle slidably mounted on said carrier iron and adapted to support a coupler, stop means in said recess engaging said stop means, a member mounted in said recess slidably mounted with respect to said carrier iron and adapted to compress said spring during movement of said member away from its central position, and releasable means movably mounted on said saddle adapted in one position to engage said member to cause the saddle to move said member against the compression of said spring during sliding of said saddle on said carrier iron and adapted in another position to allow sliding movement of said saddle on said carrier iron without compressing said spring.

5. In a centering device a carrier iron having top and bottom horizontal walls and a vertical connecting side wall, a saddle slidably mounted on said top wall and adapted to support a coupler, a spring carried by said carrier iron positioned between said top and bottom walls, abutment means fixed to said carrier iron and engaging the ends of said spring, a member slidably mounted within said carrier iron engaging the ends of said spring and adapted to compress the latter upon movement of said member away from its central position, and means on said saddle adapted to be moved into and out of engageable relation to said member for releasably connecting said saddle to said member.

6. A centering device comprising a carrier iron having a recess therein, a saddle slidably mounted on said carrier iron and adapted to support a coupler, a spring positioned between stops in said recess and adapted to be placed under compression therein, a member mounted in said recess embracing said spring and adapted to compress the latter upon moving relative to said carrier iron in a direction away from its central position, and means releasably connecting said saddle to said member, said means comprising stops on said member and a lock member pivotally attached to said saddle adapted to engage said stops to lock said member and said saddle from relative movement therebetween.

7. A centering device comprising a carrier iron having a recess therein, a saddle slidably mounted on said carrier iron and adapted to support a coupler, a spring positioned between stops in said recess and adapted to be placed under compression therein, a member mounted in said recess embracing said spring and adapted to compress the latter upon moving relative to said carrier iron in a direction away from its central position,

and means releasably connecting said saddle to said member, said means comprising a lock member pivotally attached to said saddle and adapted to engage said first named member to lock the latter from movement relative to said saddle.

8. In a centering device a carrier iron, a saddle slidably mounted on said carrier iron and adapted to support a coupler, spring means positioned between stops in said carrier iron for normally maintaining said saddle in central position, a member carried by said carrier iron embracing said spring and adapted to compress the latter upon movement of said member relative to said carrier iron, and means pivotally attached to said saddle and adapted when in lowered position to engage said member to lock said saddle and said member from relative movement therebetween and when in raised position to disconnect said saddle from said member.

9. In a centering device a carrier iron, a saddle slidably mounted on said carrier iron and adapted to support a coupler, a yoke, a spring positioned between stops in said carrier iron for centering said yoke, means for releasably connecting said saddle and said yoke, said means comprising stop lugs on said yoke and a pivotally mounted lock member on said saddle adapted to engage said lugs when said member is in locked position, each of said lugs having a sloped surface thereon, and means on said lock member adapted upon movement of said saddle from released displaced position toward locked position to engage said sloped

surface of one of said lugs to cause said lock member to pivot upwards to enable the same to drop into locked position when said saddle is in central position.

5 10. In a centering device a carrier iron, stop means on said carrier iron, spring means engaging said stop means, a yoke engaging the ends of said spring means, a coupler supporting member slidably mounted on said carrier iron, and means

10 15 on said supporting member adapted to engage said yoke to compress said spring means upon sliding movement of said supporting member on said carrier iron, from its central position said last named means comprising a member mounted on said supporting member adapted to be moved into and out of engageable relation with said yoke.

11 20 In a centering device a carrier iron, a coupler supporting member slidably mounted on said carrier iron, a yoke carried by said carrier iron slidably relative thereto, spring means positioned between stops in said carrier iron for normally centering said yoke, stop lugs on said yoke, brackets on said member, a lock member pivoted to said brackets and embracing said lugs when in locked position to lock said yoke and supporting member from relative movement therebetween, and means on said lock member for pivoting the latter to unlocked position, allowing said supporting member to move relative to said yoke.
